(57) **CLAIM**

The ornamental design for a ring, as shown and described.

DESCRIPTION

FIG. 1 is a front left perspective view of a ring showing my new design.

FIG. 2 is a front right perspective view thereof;

FIG. 3 is a right side view thereof, the left side view being a mirror image;

FIG. 4 is a top view thereof, the bottom view being a mirror image;

FIG. 5 is a cross-section view of the ring taken in the direction of line 5-5 of FIG. 4; and,

FIG. 6 is a cross-section view of the ring taken in the direction of line 6-6 of FIG. 4.

The broken lines shown in the drawings depict portions of the ring that form not part of the claimed design.

1 Claim, 3 Drawing Sheets
